JUAN DE DIOS MORENO, OF SAN FRANCISCO, CALIFORNIA.

REVERSIBLE COMB.

Application filed November 29, 1926. Serial No. 151,478

This invention relates to improvements in combs, and has particular reference to a reversible comb.

The principal object of this invention is to produce a comb which may be employed in such a manner that either the coarse teeth or the fine teeth may be brought into instant use by a simple manipulation of the wrist.

10 A further object is to provide a comb having a central portion acting as a hand hold and so constructed that the comb may be manipulated without the danger of dropping, even though the hands be slippery, 15 as a hair dresser's often are when shampooing and the like.

A further object is to provide anchor teeth at both ends of the two sets of teeth, which anchor teeth serve to prevent breaking of 20 the teeth.

A still further object is to provide a comb which is sanitary, economical to manufacture and one which is pleasing in appearance.

25 Other objects and advantages will be apparent during the course of the following description.

In the accompanying drawings forming a part of this specification and in which like numerals are employed to designate like parts throughout the same,

Figure 1 is a side elevation of my improved comb,

Figure 2 is a top plan view of Figure 1 and,

Figure 3 is a cross section taken on the line 3—3 of Figure 1.

At present time it is customary to provide both fine and coarse teeth upon the same side of the comb, the result being that when the user wishes to go from the fine teeth to the coarse teeth, it is necessary to turn the comb end for end, which is an awkward procedure, particularly if the hands are at all slippery. I have therefore devised a comb comprising three sections, a coarse section, a fine section, and a hand hold section. The hand hold section serves to join the coarse section and the fine section, the teeth of the fine section and the teeth of the coarse section being disposed in opposite directions. As a result of this construction a person may grasp the comb between the thumb and first finger of the hand and by simply rotating

the comb in a vertical plane, either the fine 55 section or the coarse section of the comb may be brought into use.

When in one position the entire comb will lie above the hand, while in other position a part of the comb will lie within the hand, 60 similar to the present day manner of using a comb.

Referring to the drawings, the letter A refers to the coarse section, the letter B the fine section and the letter C the hand hold 65 section.

It will be noted by viewing Figures 1 and 2, that the hand hold section is provided with ribs 5 and 6 diagonally disposed upon the opposite sides of the hand hold section. 70 The teeth 7 of the coarse section, point upwardly as shown in Figure 1, while the teeth 8 of the fine section point downwardly, the result being that when the operator grasps the comb by the hand hold section, allowing 75 the thumb to rest upon one side thereof and the first finger resting upon the other side thereof, a firm grip will be had due to the ribs 5 and 6. If the thumb and finger engage the handle at substantially the point 80 9, the fine section B will lie within the hand, therefore any downward pressure upon the coarse section will automatically move the back of the fine section against the palm of the hand, the thumb and finger acting as a 85 fulcrum.

Suppose it is now desired to use the fine section, the same is swung upon the fingers, the fingers remaining in their same position with the result that the fine section will be 90 moved into the position where the teeth are pointing upwardly and the coarse section will move into the position pointing downwardly, but they will now rest on top of the hand and the second finger will rest under 95 the hand hold section at approximately the point 11, therefore the comb can again be gripped very securely as the ribs 5 and 6 will prevent the slipping of the fingers from the hand hold section that will enable the operator to hold the comb tightly against the second finger and the back of the hand.

We have been assuming that the comb was being used in such a manner that the teeth of the portion being used were pointing upwardly. We will now assume that the comb is turned over upon a horizontal axis, the direction of the slant of the ribs

5 and 6 will be reversed but the action of the comb will remain the same.

It will thus be seen that I have produced a comb which is easy to handle and one wherein there is very little danger of pulling the hair with that portion of the comb not being used.

It will further be noted that I have provided the anchor teeth 12 adjacent the ends 10 of both the fine section and the coarse section, which anchor teeth serve to prevent the breaking of the teeth as is now quite common in many forms of combs.

Having thus described my invention, I claim:—

In a comb, a coarse section, a fine section, a hand hold section connecting said coarse section and said fine section, said hand hold section having outstanding ribs formed on the opposite sides thereof and diagonally disposed with relation to the teeth thereof, and the teeth of said coarse section and said fine section being disposed in opposite directions.

In testimony whereof I affix my signature.

JUAN DE DIOS MORENO.
